UNITED STATES PATENT OFFICE.

JASPER JEROME SABIN, OF COUPEVILLE, WASHINGTON.

MECHANICAL TOY.

1,214,377.

Specification of Letters Patent. Patented Jan. 30, 1917.

Application filed May 13, 1916. Serial No. 97,315.

To all whom it may concern:

Be it known that I, JASPER J. SABIN, a citizen of the United States, and a resident of Coupeville, in the county of Island and State of Washington, have invented a new and useful Improvement in Mechanical Toys, of which the following is a specification.

My invention is an improvement in mechanical toys, and has for its object to provide a toy of the character specified, especially adapted to be arranged on the hood of a motor vehicle, weather vane, cupola or the like, wherein the representation of a figure, as for instance a man, is mounted to rotate on a vertical axis, wherein the head is mounted to turn with respect to the body, and wherein the arms are provided with blades and they are mounted to rotate on an axis transverse to the turning movement of the head and the rotation of the body, and wherein the arms are so connected to the head that during their swinging or rotating movement they move the head from side to side, the head facing each arm during the striking or downward movement of the arm.

In the drawings: Figure 1 is a front view of the improved toy in place on the hood of a motor vehicle, Fig. 2 is a vertical section 30 through the toy, and Fig. 3 is a perspective view of the connection between the arms and the head.

The present embodiment of the invention is shown mounted on the filling plug 1 of a motor vehicle 2. A pedestal 3 is provided for supporting the figure, to be described, and the said pedestal has a depending journal pin 4, which is rotatably mounted within a threaded stem 5, which passes through an opening in the filling plug and is engaged by lock nuts 5^a above and below the plug to hold the stem in place. A ball 3^a is mounted in the recess of the stem 5, and the lower end of the journal pin rests upon the ball. A cap 7 is threaded onto the upper end of the stem, and the journal pin 4 is reduced adjacent to the pedestal to form a shoulder for engaging the cap to limit the upward movement of the journal pin with respect to the stem. The pedestal is secured to the legs of the figure 6 by means of screws 4^a or the like. The head 8 has a recess 9 which receives a reduced neck 10 at the upper end of the body, and the said head rotates on the neck, being connected to the body by a vertical shaft 11.

The body is provided with a chamber 12 between the neck and the waist, and the shaft 11 passes through this cavity or chamber, being journaled at its lower end in a step bearing 13 at the bottom of the cavity. The upper end of the shaft passes through registering openings in the neck and in the head, and the upper end of the shaft is secured to the head by a pin or screw 14, for constraining the head to turn with the shaft.

A shaft 15 is journaled transversely of the body and the chamber 12 and the ends of the shaft are threaded as shown, and extend through arms 16. Bearing plates 17 are arranged at the ends of the shaft, the bearing plates being secured to the body and openings lead from the chamber outwardly at the shoulders of the figure, and the bearing plates 17 are arranged over these openings, being secured to the figure by means of screws as shown.

Each arm 16 is held to the adjacent end of the shaft by means of nuts 18, which are threaded on to the ends of the shaft on opposite sides of the arms, and the nuts are countersunk as shown. The arms are thus rigidly secured to the shaft, and the arms are mounted to rotate with the shaft. The representation of a blade or sword 19 is rigidly secured to each arm at the hand, and these blades are so arranged that when impinged upon by air currents the shaft 15 will be rotated, the arms swinging about under the influence of the wind to rotate the shaft.

As seen in Fig. 2 one of the blades 19 is in the plane of the figure while the other is perpendicular to the plane, that is, the blades are arranged in planes at right angles to each other. When the figure is in the position of Fig. 1 air currents impinging upon the lowermost blade 19 will tend to swing the figure on its vertical axis and will also tend to swing the said arm rearwardly and upwardly. This movement will bring the uppermost blade with its plane perpendicular to the direction of the air currents, and there will be a continuous oscillation or rotation of the figure and of the arms while the vehicle is in motion or while the air currents are impinging against the blades.

The shaft 15 is so connected to the shaft 11 that when the shaft 15 rotates the shaft 11 will be oscillated. The shaft 11 is provided with an integral loop 20 intermediate

its ends through which the shaft 15 extends, and the shaft 11 is provided with a cross head 21 just above the loop.

The ends of the cross head or pin 21 are 5 adapted to be engaged by radial pins 22 on the shaft 15, and it will be evident that when the shaft 15 is rotated these pins 22 will engage the opposite ends of the cross head 21 and will oscillate the shaft 11 in 10 opposite directions to cause the head 14 to swing. The pins 22 are so arranged with respect to the arms that the pin 22 adjacent to the right arm for instance, will engage the cross head 21 as the left arm moves 15 into upright position, and will cause the head to turn toward the left arm as the said arm moves downward in the act of striking. The head will thus follow the striking movement of each arm, turning toward 20 each arm as it swings downward. The ends of the loop 20 by their engagement with the shaft 15 will limit the swinging movement of the head in either direction.

It will be noticed from an inspection of 25 Fig. 2 that that portion of the body above the chamber 12 is separable from the body, being held to the body and to the bearing plates 17 by the screws. This portion of the body may be removed to permit access 30 to the cavity and the mechanism contained therein.

I claim:—

1. A mechanical toy of the character specified, comprising the representation of 35 a figure having a chamber in the upper portion thereof, a head mounted to rotate on the figure on a vertical axis, a shaft journaled transversely of the representation near the top thereof and extending across the chamber, arms secured to the ends of the shaft and extending in opposite directions, each having the representation of a blade or sword in the hand thereof, and the said blades having their planes perpendicular to 40 each other to constrain the shaft to rotate when the wind impinges against the blades, a pedestal upon which the figure is mounted to rotate on a vertical axis, and a connection between the head and the shaft for constraining the head to turn toward each arm as it moves downward, said connection comprising a shaft journaled in the upper part of the figure and rigid with the head and having a loop intermediate its ends through 45 which the first-named shaft extends, said last-named shaft having a cross head above the first-named shaft and the first-named shaft having radial pins for alternately engaging the ends of the cross head.
- 50 2. A mechanical toy of the character specified, comprising the representation of a figure having a chamber in the upper por-

tion thereof, a head mounted to rotate on the figure on a vertical axis, a shaft journaled transversely of the representation 65 near the top thereof and extending across the chamber, arms secured to the ends of the shaft and extending in opposite directions, each having the representation of a blade or sword in the hand thereof, and the 70 said blades having their planes perpendicular to each other to constrain the shaft to rotate when the wind impinges against the blades, a pedestal upon which the figure is mounted to rotate on a vertical axis, and a 75 connection between the head and the shaft for constraining the head to turn toward each arm as it moves downward.

3. A mechanical toy of the character specified, comprising the representation of 80 a figure having a chamber in the upper portion thereof, a head mounted to rotate on the figure on a vertical axis, a shaft journaled transversely of the representation near the top thereof and extending across 85 the chamber, arms secured to the ends of the shaft and extending in opposite directions, each having the representation of a blade or sword in the hand thereof, and the said blades having their planes perpendicular to each other to constrain the shaft to rotate when the wind impinges against the 90 blades, and a connection between the head and the shaft for constraining the head to turn toward each arm as it moves down- 95 ward.

4. A mechanical toy of the character specified, comprising the representation of a figure having a chamber in the upper portion thereof, a head mounted to rotate on 100 the figure on a vertical axis, a shaft journaled transversely of the representation near the top thereof and extending across the chamber, arms secured to the ends of the shaft and extending in opposite directions and having means for constraining the 105 shaft to rotate when the arms are engaged by air currents, and a connection between the head and the shaft for constraining the head to turn from side to side as the shaft 110 rotates.

5. A mechanical toy of the character specified, comprising the representation of a figure consisting of a body, arms rigidly connected and mounted to rotate with respect to the body on an axis transverse to the body, said arms extending in opposite directions, a head rotatably connected with the body to rotate on a vertical axis, and a connection between the head and the arms 115 120 to constrain the head to turn from side to side as the arms rotate.

JASPER JEROME SABIN.
